UNITED STATES PATENT OFFICE.

WILLIAM S. MILLS, OF TRUMBULL, AND HECTOR E. BISAILLON, OF BRIDGEPORT,
CONNECTICUT.

STOP-MOTION DEVICE.

1,424,844.

Specification of Letters Patent. Patented Aug. 8, 1922.

Application filed June 11, 1921. Serial No. 476,824.

To all whom it may concern:

Be it known that we, WILLIAM S. MILLS and HECTOR E. BISAILLON, citizens of the United States, residing, respectively, at 5 Trumbull and Bridgeport, in the county of Fairfield and State of Connecticut, have invented or discovered certain new and useful Improvements in Stop-Motion Devices, of which the following is a specification, reference being had therein to the accompanying drawings.

This invention relates to a stop motion device for sewing machines or the like and comprises certain improvements on the stop motion devices covered by our U. S. Patents 15 No. 1,359,266, dated November 16, 1920, and No. 1,380,003, dated May 31, 1921.

In the construction shown by our last-named patent the pivoted brake shoe which 20 engages the sewing machine fly wheel, to stop the machine, is liable to be tilted by the rotation of the fly-wheel, when the said brake shoe is released from the fly-wheel and the machine is next started, such tilting 25 causing the brake shoe to be somewhat in frictional contact therewith, such frictional contact being sufficient in some instances, to cause heating of the fly-wheel, thus resulting in some loss of power as well as inconvenience to the operator who may wish to 30 place her hand on the wheel, which sometimes gets unpleasantly hot. In accordance with the present invention this result is prevented by a stop which will prevent tilting 35 movement of the pivoted brake shoe when the machine is started.

Also in the construction shown in our last-named patent the stopping lever which carries the brake shoe is acted on by a spring 40 which releases the brake shoe and moves the said lever towards its operating cam. In the present improved construction the said lever is positively operated in both directions to withdraw the brake shoe from contact 45 with the fly wheel and also to force said shoe in contact with said fly-wheel, as will hereinafter more fully appear.

Also in the construction shown in our last-named patent the upper thread guides 50 which hold the threads in proper positions to direct the threads into the slits of the tripping levers comprise plain holes through the thread guide plates. When the machine is running rapidly and the thread is passing swiftly through the said thread guide 55 holes kinks will sometimes occur in the

thread, thus endangering the breakage of the latter. The present construction comprises a thread guide consisting of a tapering hollow part or trumpet which will serve 60 to straighten out any kinks which may occur in the thread passing to the slotted tripping arm or lever; a plurality of these tapering hollow parts or trumpets being provided in case the invention is to be used in 65 connection with a multiple sewing machine.

In the accompanying drawings Fig. 1 is an elevation of the improved stop-motion device. Fig. 2 is an end view of the same looking from the left, Fig. 1. Fig. 3 is a 70 plan view of the improved stop-motion device, Fig. 4 is a sectional elevation, looking from the right, Figs. 1 and 3, and Fig. 5 is a detail view of the tripping rock-shaft and connected parts. 75

Referring to the drawings, 12 denotes a bracket or support which may be attached to a work bench conveniently adjacent to a sewing machine in connection with which the improved stop motion device is to be 80 used, said bracket having uprights 13 and 14, affording bearings for a rock-shaft 15 provided at its forward end, inside of the upright 13, with an arm 16 having at its upper end a pin 17 engaging the lower end of 85 a latch-lever 18 pivoted to said upright 13 and having a bevelled or rounded upper end adapted to be engaged by a finger 21 on a holding latch 22 carried by a tripping rock-shaft 23 journalled in bearings afforded by 90 the upwardly projecting lugs 24 at the upper end of the upright 13. The latch-lever 18 is provided at its lower end with an inclined finger 19 rearward of which is a lug 95 20 affording a notch arranged to be entered by the pin 17 on the arm 16 of the rockshaft 15, as in the construction shown and described in our Patent No. 1,380,003, of May 31, 1921.

The tripping rockshaft 23, in the form 100 of the invention herein shown, carries a single tripping arm 26 having a narrow slit 28 permitting the free passage of the thread but not of knots or lumps in the thread, so that said tripping arm will be tripped or 105 moved downwardly slightly when engaged by a knot or lump in the thread. The slit 28 has a V-shaped or inwardly tapering open end 29 which serves to facilitate the entrance of the thread in said slit, and which also 110 serves, in conjunction with the thread guides 30 and 31, arranged on opposite sides of

said tripping arm, to permit the escape of the knots or lumps from the tripping arm when the latter is moved downward in the tripping operation, thereby avoiding breaking 5 the thread by the machine, which is objectionable, even though the thread has to be broken by the attendant to remove the knot or lump.

The holding latch 22 is normally held in 10 yielding contact with an adjustable stop-pin 32 tapped in a lug 33 on the upright 13 and held in any desired position of adjustment by a lock-nut 34. This holding of the latch 22 against the top of the pin 32 is effected 15 by the coil spring 35 connected at its upper end to a hooked arm 36 on the rock-shaft 23 and connected at its lower end to a lug 37 on a bracket 38 adjustably attached to the upright 13 by a set screw 39 passing through 20 a slot in said bracket.

The upper or entering thread guide 30 consists of a hollow, interiorly tapering part or trumpet which will serve to straighten any kinks which may occur in the thread 25 rapidly passing to the slotted tripping arm 26, thus avoiding breakage of the thread from this cause. This upper thread guide is carried by an arm 40 having a hooked lower end affording a slot by which the said 30 arm may be adjustably attached to the upright 13 by a set screw 41, such attachment permitting the said arm to be adjustable both longitudinally and axially. Similarly, the thread guide 31 is carried by an arm 42 35 also having a hooked lower or inner end affording a slot by which the said arm is adjustably attached to the upright 13 by a set screw 43 which also affords longitudinal and axial adjustments of the said thread 40 guide arm. This construction affords double adjustments of the said thread guides, as in the construction set forth in our patent of May 31, 1921, but by simpler means.

The rockshaft 15 is provided at its rear 45 end with an arm 44 formed integral with the setting handle 45 which is attached to said rock shaft by a set screw 46. The arm 44 carries a pin 47 entering a slot in the long arm of a lever 48 pivotally mounted in a 50 yoke 49 having a threaded shank 50 which is tapped in a lug 51 on a plate 52 which is to be attached to the sewing machine table or work bench beneath the driving or power shaft 53 of the sewing machine, said power 55 shaft carrying a fly-wheel 54 having an integral grooved pulley portion 55. The yoke 49 is held in any desired position of adjustment by a lock nut 56 on the threaded shank 50 of the said yoke. Pivotally 60 mounted on the short arm of the lever 48 is a brake shoe 57, of usual construction, which is arranged closely adjacent to the grooved pulley portion 55 of the fly wheel 54 so that when the latch lever 18 is released 65 from the finger 21 on the holding latch 22

the rockshaft 15 will be turned by the torsional coil spring 58 thereon, thus causing the lever 48 to be operated to force the brake shoe into contact with the grooved pulley portion of the fly-wheel by the stress 70 of said torsional spring, and thereby stopping the machine. The driving or power shaft 53 is driven by a light belt running over the grooved pulley 55, and the stress of the spring 58 is sufficient to overcome the 75 frictional hold of said belt on said pulley, so that the belt, which in practice is run rather loose, will slip on the pulley 55 when the machine is stopped. The torsional spring 58 is connected at one end to the upright 80 14 and is connected at its other end to a collar 15^a attached to the rock shaft 15. This collar, when its holding set screw is loosened, may be turned on the shaft 15 to give the spring 56 any desired stress or 85 tension.

When the brake shoe is released from the fly wheel pulley and the machine is started, with the fly wheel running in the direction noted by the arrow in Fig. 2, the running 90 fly wheel pulley will have a tendency to tilt the said brake shoe in such a manner that some portion thereof may be in contact with the said grooved pulley portion of the fly wheel from which it had been released when 95 the parts were reset before starting the machine. To prevent this tilting movement of the brake shoe a curved stop arm or wire 59, attached at one end to the lug 51 on the plate 52 is provided, the outer end of said 100 arm being in contact with or closely adjacent to the lower side of the brake shoe when the latter is released from the grooved pulley part of the fly-wheel. Thus any 105 tilting of the brake shoe which might cause some part thereof to be in frictional contact with the running grooved pulley part of the fly wheel will be prevented by said stop.

The tripping arm 26 and the holding arm 22 are both attached to the tripping rock-shaft 23 by a set-screw 27, and as said arm and latch are arranged between and closely adjacent the lugs 24 in which said rock-shaft is mounted they will prevent endwise movement of said rockshaft in its bearings. 110 115

In the operation of this device when a knot or lump in the thread engages the slotted tripping arm 26 the said tripping arm will be moved to the right, looking at Fig. 2, thus also moving the holding latch 22 connected with the said tripping arm through the tripping rock-shaft 23 and thereby releasing the finger 21 on the said holding latch 22 from the latch-lever 19, thus releasing said holding latch and permitting 120 the torsional spring 58 to turn the rock-shaft 15 to force the brake shoe into contact with the grooved pulley portion of the fly wheel to stop the machine, the said latch-lever being by this operation moved by the 125 130

pin 17 on the arm 16 of the said rockshaft 15 to the position indicated by dotted lines in Fig. 2. When the parts are to be reset after stopping the machine the handle 45 on the rockshaft 15 is lifted from the position shown in dotted lines in Fig. 2 to the position shown in full lines in said figure, and in this operation the pin 17 will engage the finger 19 at the lower end of the latch lever 18, thus returning said latch-lever to its normal position in engagement with finger 21 on the holding latch 22. In this resetting movement the yielding holding latch 22 will be lifted slightly by the rounded or bevelled upper end of the latch-lever 18 to permit said end to pass by the finger 21. From the foregoing it will be understood that the present invention provides certain improvements on the stop-motion devices of our patents hereinbefore referred to by which the construction of the parts is simplified and certain objections heretofore existing are remedied.

Having thus described our invention we claim and desire to secure by Letters Patent:

1. In a stop-motion device, the combination with a power shaft provided with a wheel to which a brake may be applied, of a tripping mechanism comprising a spring-actuated rock-shaft, a setting handle attached to said rock-shaft and having an arm provided with a pin, a bracket supporting said rock-shaft, a lever having a slot entered by said pin, a brake device carried by said lever and arranged to act on said wheel, a latch-lever mounted on said bracket and operatively connected with said rock-shaft, a spring-held tripping rock-shaft supported by said bracket and carrying a holding latch having a finger normally engaging said latch-lever and holding the stop-motion device inactive, a tripping arm carried by said tripping rock-shaft and provided with a narrow slit permitting free passage of a thread, but adapted to be tripped by knots or lumps in the thread to release said latch from said latch-lever and thus render the stop-motion device operative to apply said brake device positively to said wheel on said power shaft.

2. In a stop-motion device, the combination with a power shaft provided with a wheel to which a brake may be applied, of a tripping mechanism comprising a spring-actuated rock-shaft, a setting handle attached to said rock-shaft and having an arm provided with a pin, a bracket supporting said rock-shaft, a lever having a slot entered by said pin, a brake shoe having a pivoted connection with said lever and arranged to act on said wheel, a support for said lever, a curved stop arm mounted on said support and having its upper end closely adjacent to said brake shoe to prevent the said shoe from tilting when the said wheel is started, a latch-lever mounted on said bracket and operatively connected with said rock-shaft, a spring-held tripping rock-shaft supported by said bracket and carrying a holding latch having a finger normally engaging said latch-lever and holding the stop-motion device inactive, a tripping arm carried by said tripping rock-shaft and provided with a narrow slit permitting free passage of a thread, but adapted to be tripped by knots or lumps in the thread to release said latch from said latch-lever and thus render the stop-motion device operative to apply said brake device positively to said wheel on said power shaft.

3. In a stop-motion device, the combination with a power shaft having a fly wheel provided with a grooved pulley, of a brake shoe adapted to engage said grooved pulley, a lever with which said brake shoe is pivotally connected, a support for said lever, an arm mounted on said support with its upper end closely adjacent said brake shoe to prevent tilting movement of the said brake shoe when released from said pulley and said wheel is started, means for holding said brake shoe out of contact with said driving pulley, positive means for forcing said brake shoe into contact with said driving pulley when said holding means are released, and tripping means for releasing said holding means, said tripping means comprising an arm having a slit permitting passage of the thread but which arm will be tripped by a lump or knot in the thread to release said holding means, thus permitting said brake shoe to be forced into contact with said pulley by said forcing means.

4. In a stop-motion device for sewing machines, the combination with a power shaft and a brake device to act on said shaft, of an operating mechanism for holding and releasing said brake device, said operating mechanism comprising a tripping rock-shaft, an upright having lugs at its top in which said rock-shaft is mounted, a tripping arm fixed to said rock shaft and having a narrow slit for the passage of the thread, said tripping arm being adapted to be tripped by lumps or knots in the thread, and a holding arm also attached to said rockshaft, said arms being between and closely adjacent to said lugs and thus serving to hold said rockshaft in place against endwise movement.

In testimony whereof we affix our signatures.

WILLIAM S. MILLS.
HECTOR E. BISAILLON.
